UNITED STATES PATENT OFFICE.

THEODORE HOLZHALB, OF BROOKLYN, NEW YORK, ASSIGNOR TO THE SEGAR STUDIOS INC., A CORPORATION OF NEW YORK.

DESIGN FOR A LIGHTING-FIXTURE BODY OR ANALOGOUS ARTICLE.

Application filed April 5, 1926. Serial No. 17,184. Term of patent 7 years.

To all whom it may concern:

Be it known that I, THEODORE HOLZHALB, a citizen of the United States, and a resident of county of Kings, city of Brooklyn, and State of New York, have invented a new, original, and ornamental Design for a Lighting Fixture Body or Analogous Article, of which the following is a specification, reference being had to the accompanying drawing, forming a part hereof.

In these drawings:

Figure 1 is a perspective view of the lighting-fixture body or analogous article; and

Figure 2 is a diagrammatic inverted plan view showing the outline of the same.

I claim:

The ornamental design for a lighting fixture body or analogous article substantially as shown.

THEODORE HOLZHALB.
